(21) Appl. No.: **29/144,426**

CLAIM

(22) Filed: **Jun. 28, 2001**

The ornamental design for a pneumatic tire tread and buttress, as shown and described.

(51) LOC (7) Cl. **12-15**

DESCRIPTION

(52) U.S. Cl. **D12/556**

FIG. 1 is a perspective view of a pneumatic tire tread and buttress showing our new design;

(58) Field of Search D12/547, 549, D12/550, 551, 553, 555, 556; 152/209.1, 209.9, 209.15, 209.13, 209.28

FIG. 2 is a front elevational view thereof;

(56) **References Cited**

FIG. 3 is a side elevational view thereof with the opposite side being a mirror image thereof;

U.S. PATENT DOCUMENTS

FIG. 4 is a greatly enlarged fragmentary perspective view thereof; and,

D423,418 S * 4/2000 Meslot et al. D12/556
6,213,180 B1 * 4/2001 Himuro 152/209.15

FIG. 5 is a cross sectional view taken on line 5—5 of FIG. 4.

OTHER PUBLICATIONS

The broken line showing of a tire sidewall and inner bead and the peripheral boundary between the tire tread and sidewall is for illustrative purposes only and forms no part of the claimed design.
